ABSTRACT OF THE DISCLOSURE

A propulsor device which is useful for propelling marine vessels is provided with a combustion chamber and tubular duct construction of special configuration and relationship to one another. The combustion chamber has a single primary opening formed in it for providing a communication between the combustion chamber and the tubular duct. A fuel and combustion-supporting gas mixture are supplied to the combustion chamber where the fuel and gas mixture are ignited to produce a detonation, chain-breaking reaction which results in the formation of a shock wave. The combustion chamber has a tapered configuration in the direction of its primary opening so that the shock wave is focused and reinforced as it exists from the combustion chamber, through the primary opening, and into the tubular duct. The shock wave strikes the surface of a liquid (water or whatever liquid medium the device is being utilized in) which is inducted into the tubular duct means prior to the detonation of the fuel and gas mixture. The tubular duct means includes an internal space, as measured between the average level of inducted liquid in the tubular duct and the level of communication between the tubular duct and the primary opening of the combustion chamber, which is greater than the internal volumetric space of the combustion chamber so that substantially all detonation gases are exhausted from the combustion chamber prior to impact of the shock wave with the liquid contained within the tubular duct means. By this arrangement, a slug of liquid is rapidly expelled from the tubular duct means, and pressure conditions within the combustion chamber are substantially reduced by the rapid movement of the shock wave out of the combustion chamber and through the tubular duct connected thereto. The lower end of the tubular duct means is curved so that a propelling force is provided when the propulsor is used in a generally upright attitude. The combustion chamber and tubular duct are related to one another so that reflected waves produced by the initial impact of the shock wave with liquid in the tubular duct are utilized to draw in additional combustion-supporting gas, and to create a turbulence of the same with fuel mixture (while at the same time avoiding a residual turbulent ignition), for a subsequent detonation cycle. The device may be used with a variety of fuels, and one example of operation utilizes hydrogen gas as a fuel, as ignited by a high energy sparking device positioned within the combustion chamber at a point which is aligned with a central longitudinal axis of the tubular duct and the primary opening of the combustion chamber.

BACKGROUND AND BRIEF DESCRIPTION OF INVENTION

This invention relates to propulsor devices which are useful for marine propulsion, and in particular, the invention is concerned with improvements in propulsor devices of a type which ignite a fuel mixture in a combustion chamber so as to expel a slug of water from a tubular duct which has one end connected to the combustion chamber and a free end which can be placed below

2

the body of a liquid in which the device is to be operated. The propulsor device of this invention has practically no moving parts of the type normally associated with internal combustion engines, and novel constructions and relationships are provided to assure a detonation which produces a shock wave for rapidly impacting a slug of water out of the tubular duct means.

Prior devices are known which attempt to expand a volume of water out of an upstanding duct communicating with a body of water in accordance with periodic explosions and expansions of gases which take place above the volume of water which is contained within the upright tubular duct. However, extensive research on this subject has failed to produce any device which is efficient in expelling slugs of water from a duct, and no known device has been developed which would be useful in a wide variety of propulsion requirements for actual marine use. Basically, prior devices have attempted to explode a gaseous fuel mixture above a slug of water contained within a tube so as to expand the slug of water out of a free end of the tube and into a body of water in which the device is operating. After each expansion of a volume of water out of the tube, a new volume is drawn back into the tube for a subsequent expulsion by a subsequent explosion in the device. However, it can be seen that a reaction force is created by the re-induction of a new volume of water into the tube after each expulsion from the tube, and thus, the net propulsive effect of such a device depends upon a difference in the rate at which water is expelled as compared to the rate at which a new volume of water is drawn back into the tube. Prior research and development on this subject has not produced a device which offers a satisfactory propulsive effect, and the present invention has discovered important and critical relationships which produce substantially improved results over anything known prior to this invention.

A number of prior attempts to device propulsor units of the type discussed above have resulted in rather complex equipment requiring carefully controlled valves for both the fuel mixture and for directing the flow of water into and out of a tubular duct associated with a combustion chamber. Certain prior art developments have completely avoided any induction of a slug of water upwardly into a tubular duct associated with a combustion chamber, and such efforts have been primarily concerned with creating venturi effects or similar reactions to obtain a propulsive component at a terminal end of an exhaust duct associated with a combustion chamber. For example, McCullum Patent 2,412,825, Dec. 17, 1946, describes a device wherein a forward motion of the device through a body of water is required to maintain a propulsive effect obtained at the end of an exhaust duct. Other devices of a similar nature are described in Wille Patent 3,232,047 and Brown et al. Patent 3,265,027.

Another line of development in this art has considered the possibility of inducting a quantity of water into a tube or chamber, and then, expelling the inducted quantity of liquid outwardly from the tube or chamber by the expansion of an ignited gas. Patents which have considered this possibility include Edlin 1,117,351, Gongwer et al. 2,522,945, Gongwer 2,714,800, and Coxe et al. 2,664,297. However, the arrangements which have been attempted involve the use of valving devices within the propulsor unit itself to control the induction and exhaustion of liquid to and from the unit together with rather complex devices for controlling the admission of fuel and air mixture to a combustion chamber associated with the device. The present invention involves substantial improvements in the type of system which inducts water, or other liquid medium, into a tubular duct for subsequent expulsion from the duct. In contrast to prior art attempts, the present invention accomplishes markedly improved

propulsion effects from much simpler equipment than has been developed before. Other prior art on this subject includes U.S. Patents 632,662, 1,799,133, 2,203,010, 2,463-820, 2,528,354, 2,885,988, 3,024,597, 3,060,682, 3,107,486, 3,137,994, 3,137,997, 3,244,374, 3,271,947, 3,279,179, and 3,303,652. Foreign patents on this subject include German Patent 841,552 and Russian Patent 154,843.

In accordance with the present invention, it has been determined that prior art arrangements have been unsatisfactory in producing a rapid expulsion of an inducted water slug from a tubular duct or chamber communicating with a combustion chamber. It is theorized that all known prior art systems have failed to produce and deliver shock waves to the surface of water contained within an induction tube. The failure to produce and deliver a shock wave may be a result of explosions and pseudo-detonations which produce a relatively mild and gradual expansion of gases within a propulsor device so as to expand a quantity of water out of an induction tube and into a watery environment in which the device is operating. It has been found that prior art systems have been inadequate in providing for controlled fuel and gas admission and a mixture within combustion chambers associated with such devices, and further, prior art systems have failed to produce shock waves which will rapidly expel water from an induction tube in a manner which will provide for efficient propulsion of a marine vessel. In complete contrast, the present invention achieves a detonation, and a shock wave is produced within a combustion chamber without interfering waves which increase pressure and reduce velocity in a given direction. The shock wave functions to sharply impact and blast a slug of water out of an associated tubular duct. Further, the present invention provides for a relatively simple device which is easily and economically manufactured, and components of the device are related to one another to achieve (a) an improved admission and mixing of fuel and gas, (b) ignition from a high energy point source, and (c) production and strengthening of a shock wave which impacts a water slug without being broken up prior to such impact. The relationship of a combustion chamber and associated tubular duct means of the present invention is such that substantially all explosion products are exhausted out of the combustion chamber prior to impact of a produced shock wave with the surface of a slug of water within the tubular duct means. There is no interference with the formation and travel of the shock wave to the water slug, and in fact, it is believed that the shock wave is strengthened by a specific configuration of the propulsor, as provided by the present invention. Improved means are provided for admitting and mixing fuel and gas mixtures into the combustion chamber of the invention device, and reflected pressure waves resulting from impact of the shock wave with water are utilized to obtain an efficient injection and mixing of fuel mixtures into the combustion chamber of the propulsor device.

The device of the present invention includes a combustion chamber means having a single primary opening formed through one end of the combustion chamber. The single primary opening provides for a communication of the combustion chamber with a tubular duct means which is connected to the combustion chamber. The tubular duct means is sufficiently long to receive inducted slugs of water into a lower portion while leaving a relatively large gas space above the average levels of inducted slugs. When certain fuels are utilized, an ignition device is positioned within the combustion chamber at a point which is approximately in line with a central longitudinal axis of the tubular duct means and the primary opening formed into the combustion chamber. Fuel and gas mixtures are admitted into the combustion chamber through passageways formed in the tubular duct means at a level which is closely adjacent to the communication of the tubular duct means with the combustion chamber. In this sense, the combustion chamber portion of the unit is essentially

a closed chamber having a single primary opening which functions both as a fuel admission and an explosion exhaust port. However, small ports for fuel admission may be provided as secondary openings into the combustion chamber for certain configurations. No valves or other movable devices are required within the combustion chamber, and the internal walls of the combustion chamber are constructed to promote, and even strengthen, a shock wave which is formed by detonation of fuel within the combustion chamber. The combustion chamber is shaped so as to direct a moving shock wave towards the single primary opening of the combustion chamber without disrupting or destroying the detonation shock wave. It has been found that if a certain space and volume is provided in a portion of the tubular duct means which is immediately downstream of the primary opening of the combustion chamber, the shock wave can reach the surface of a slug of water contained within a more remote portion of the tubular duct means without being disrupted or broken up during its entire travel from the combustion chamber. The result of this improved arrangement is that there is a very sharp impact of a shock wave with a water slug carried within the tubular duct means, and there is a rapid expulsion of the water slug from the tubular duct means, as contrasted with prior art device which can be characterized as pushing or expanding water from a tube at a relatively slow rate. The very rapid expulsion of a slug of water from a tubular duct results in substantially improved propulsive effects, and the net propulsion of the device of this invention is much greater than that achieved with prior systems even though the present invention also inducts a new slug of water back into the tubular duct means after each cycle of operation. Although the net propulsive effect of the present invention is sufficiently high to permit the use of a tubular duct having merely a curved outlet end, it is also possible to further improve the performance of the device of this invention by adding auxiliary devices for augmenting the thrust of the rapidly expelled water slug.

The present invention is especially useful for propelling marine vessels, and the simplified constructional features which are provided by the present invention permit the safe use of hydrogen gas as a combustion fuel. However, it has been found that a wide range of fuels, including fuels in powder form, can be used in the device of this invention because of the vastly improved turbulence which is created for the mixing of fuel within the combustion chamber. Also, the device of the present invention is useful for non-marine applications, such as in the production of shock waves in a liquid medium, and any application where it is desirable to expel slugs of liquid at a rapid rate. It is possible to modify the device of this invention for use in pumping and similar applications.

The present invention also provides for a substantially improved ignition system for use with a propulsor of the type described above. The improved ignition system may be solid state and includes a pulse generator having features which permit regulation of operating frequency of the propulsor unit.

These and other features and advantages of the invention will become apparent in the more detailed discussion which follows, and in that discussion, reference will be made to the accompanying drawings as described below.

DETAILED DESCRIPTION OF INVENTION

Referring to FIGURE 1, the general assembly of a 55 novel propulsor device of this invention is illustrated. The propulsor device is shown in a generally upright attitude for use in propelling marine vessels through a body of water. However, it is to be understood that the propulsor device of this invention may be used in other attitudes, and also, it may be used for purposes other than propelling vessels through water. Throughout this application, the device will be referred to as a propulsor device, and it is intended that the general term "propulsor" encompass any use or adaptation wherein the principles of the present invention can be utilized to rapidly propel quantities of liquid. Thus, the device is not limited to marine propulsion uses, and it may be utilized for pumping situations and in uses where liquids other than water are drawn into and expelled out of the device. The basic propulsor device comprises a combustion chamber portion 10 which communicates with a tubular duct means 12. A terminal end portion 14 of the tubular duct means is curved, and the terminal end portion is open at 16. The combustion chamber 10 and tubular duct 12 may have generally circular cross section. Additional terminal ends 14 may be provided if desired, and valving or jetting devices may be included, at the junction of the tubular duct 12 with the plurality of curved ends 14, to dictate a direction of fluid flow into and out of selected end portions.

When the illustrated propulsor device is used in ma-

rine applications, a quantity of water is received within the tubular duct means 12 for being rapidly expelled from the open end 16 of the device. Rapid expulsion of the quantity of liquid from the tubular duct means 12 is accomplished when a detonation, chain breaking, type of reaction takes place within the combustion chamber 10. In accordance with the developments and discoveries of the present invention, critical relationships have been devised for producing a shock wave within the combustion chamber 10, and the shock wave is delivered to the tubular duct means 12 to strike and rapidly expel water out of the tubular duct means 12. In the general arrangement shown in FIGURE 1, a fuel is admitted to the combustion chamber 10 by way of a central supply conduit 18 having secondary conduits 20 leading through a portion of the propulsor device so as to introduce fuel into the combustion chamber portion 10. Also, air passageways 22 are formed through a portion of the propulsor device so that combustion-supporting air can be drawn into the device when required. An igniter 24 is provided to produce a high energy (approximately 15,000 volts) spark within the combustion chamber 10 for initiating a shock wave formation within the chamber. The igniter 24 is connected to a suitable source of electrical energy, and periodic sparking of the igniter is accomplished with timing devices associated with the propulsor ignition equipment. An adjustable bracket means 26 may be provided for supporting the conduits 18 and 20 together with a distribution coupling 28.

The general arrangement which has been just described for the FIGURE 1 illustration provides for a propulsor device which has an overall configuration somewhat similar to devices attempted and tried in the prior art mentioned above. However, applicant has innovated a propulsor device which offers substantially, and even unexpectedly, improved performance over anything known to him prior to this invention, and certain critical relationships and constructional features are required to accomplish the very desirable results of shock wave formation and very rapid expulsion of water from the tubular duct means 12. Prior art devices have probably produced temporary shock waves (which quickly break down and dissipate in a general deflagration-type explosion), and such prior attempts have accomplished only an inefficient movement of a quantity of water out of upstanding tubes associated with the prior art devices. A comparison of prior art devices with the present invention would contrast what amounts to an expansion of gases and a subsequent pushing of water out of a tube with applicant's rapid expulsion or blasting of a quantity of water out of a tube. Prior art explosions have had a tendency to penetrate a water column contained within a tube, and this results in inefficient expulsion of water from the tube. Applicant's improved performance is a result of a shock wave being formed and delivered to the quantity of water which is contained within the tubular duct means 12, and the shock wave strikes the surface of the water with sufficient force to cause a rapid expulsion of the quantity, or slug, of water from within the tube. The striking of a shock wave with the surface of a quantity of water in the tubular duct means 12 may be compared to what happens when one billiard ball strikes another to relay its energy into a movement of the second billiard ball. In a similar manner, a complete slug of water is rapidly expelled out of the tubular duct means 12 with the device of this invention, and all water and combustion products are removed from both the combustion chamber 10 and the entire tubular duct means 12 as a result of the rapid expulsion of water from the tubular duct means. It can be appreciated that a low pressure condition is created within the propulsor device during the expulsion cycle, and at this point, fuel and air are inducted or admitted into the device to prepare the combustion chamber for a subsequent detonation and formation of a shock wave.

It has been found that a successful shock wave forma-

tion is a result of certain critical relationships that must exist in a propulsor device of the type contemplated by the present invention. FIGURE 2 illustrates a vertical cross-sectional view of a portion of a propulsor device to show relationships which exist between the combustion chamber portion 10, a tubular duct means 12 which communicates therewith, and passageways 30 which function to admit fuel or air, or both. Unlike prior arrangements, the combustion chamber portion 10 of the present invention is essentially a closed chamber having only a single primary opening 32 communicating into the chamber. The single primary opening 32 can be considered the cross-sectional opening which exists between the connection of the combustion chamber interior to the internal bore through the tubular duct means. No separate valving devices are required for an operation of the propulsor device of this invention, and therefore, the combustion chamber can consist of a very strong construction having a closed end 33 for producing a detonation, chain breaking, type of reaction. The single primary opening 32 forms a direct communication between the combustion chamber portion 10 and the tubular duct means 12, so that a shock wave which is formed in the combustion chamber can be delivered down the tubular duct means 12 to the surface of a quantity of water contained within the tubular duct means. It has been found that a preferred construction of the combustion chamber 10 provides for a generally tapered internal configuration for the chamber. The internal walls of the combustion chamber are tapered so as to converge as they extend from a closed end of the chamber (where the igniter means 24 is located) towards the primary opening 32 leading to the tubular duct means 12. Although a range of tapers may be utilized in various constructional embodiments of the present invention, it has been found that an average taper within the range of 5 degrees to 45 degrees (as related to an axis parallel with the central longitudinal axis of the propulsor unit) is desirable, and FIGURE 2 illustrates an example of a preferred construction wherein a taper of approximately 15 degrees is provided. Also, it has been found that compound tapers may be utilized wherein an upper portion of the combustion chamber 10 consists of a lesser taper than a lower portion of the combustion chamber, but the compound tapers should provide an average taper from one end of the chamber to the other within the range mentioned above. Since the igniter means 24 is located in a closed end 33 of the combustion chamber, it is possible to produce a detonation reaction which forms a shock wave within the chamber. By positioning the igniter means 24 in alignment with the central longitudinal axis of the tubular duct means 12 (and of the primary opening 32), the shock wave is directed, and even strengthened, in its travel towards the primary opening of the combustion chamber 10 and into the tubular duct means 12. Thus, a mixture of fuel and combustion-supporting air, or gas, can be ignited within the combustion chamber 10 by a single point source, high energy, spark to produce a shock wave which is delivered down the tapered configuration of the combustion chamber to the surface level of water contained within the tubular duct means 12. It is important that the tubular duct means have an internal diameter which is the same as, or greater than the diameter of the primary opening 32 so that the formed shock wave is not broken up in its travel from the combustion chamber 10 into the tubular duct means 12. This relationship is shown in the sectional view of FIGURE 2.

FIGURE 2 also illustrates certain critical relationships in the propulsor device for inducting or admitting combustion-supporting gas into the combustion chamber prior to each detonation within the chamber. As discussed above, passageways 22 are provided through a portion of the propulsor device for admitting air, or other gas, into the combustion chamber 10. As shown in FIGURE 4, the passageways 22 may comprise bores which are positioned about the device in the same horizontal plane

as the fuel admission bores 30, and the passageways 22 communicate directly with an outside atmosphere surrounding the propulsor device. Since relatively low pressure conditions are created within the combustion chamber 10 after each detonation, it is possible to induct air, or other gas, into the combustion chamber 10 after each detonation. The passageway 30 which is illustrated in FIGURE 2 is shown in communication with a fuel inlet conduit 20, but similar passageways 22 communicate directly with the atmosphere, as shown in FIGURES 1 and 2. Although the passageways 22 and 30 may be formed in various positions through portions of the propulsor device, it is preferred that the combustion-supporting gas passageways 22 be formed in close proximity to the communication of the combustion chamber 10 with the tubular duct means 12. This is the arrangement shown in FIGURE 2 wherein the passageway 30 (and similar passageways 22 on the same horizontal plane) are formed to enter the propulsor device just below the primary opening 32 of the combustion chamber 10. In the particular embodiment of FIGURE 2, the openings 22 and 30 are formed through a ring portion 34 which is formed integrally with the main body of the combustion chamber 10. The ring portion 34 may have a channel 36 formed about its outer circumference to receive stainless steel turnings 38 as a fire retardant packing about the entire ring formation 34. The fire retardant packing prevents an escape of flame or sparks from the combustion chamber 10 when premature or incorrect ignition takes place. An outer ring member 40 functions to hold the packing 38 in place within the channel 36, and also the conduits 20 can be supported by threaded connection tubes 42 which are carried in the outer ring 40. In the embodiment of FIGURE 2, there is also provided an integral depending skirt portion 44 which comprises a further extension of the combustion chamber 10. The depending skirt portion 44 is annular in form and functions to receive an upper end of the tubular duct means 12 when the propulsor device is assembled. As discussed above, the internal diameter of the tubular duct means 12 is substantially constant throughout its entire length so that no restrictions interfere with the rapid expulsion of a slug of water out of the lower end of the tubular duct means 12. However, it is preferred to provide a configuration at the level of induction of combustion-supporting gas, which will prevent an escape of pressure out of the passageways 22 and 30 during a detonation formation of a shock wave within the combustion chamber 10. Accordingly, a separate sleeve member 46, having a tapered configuration, is carried within the depending skirt 44 so as to provide a venturi effect for the passageways 22 and 30. The separate sleeve member 46 may be considered a part of the upper end of the tubular duct means 12 since its internal bore is coextensive with the internal bore of the tubular duct means. It can be seen in FIGURE 2 that the general taper of the combustion chamber 10 interior converges towards the primary opening 32. At that level, combustion-supporting gas is inducted into the device, and a slight diverging taper is provided by the sleeve member 46 so that there is no disruption of the shock wave as it travels past the passageways 22 and 30. Also, it is important that the lowermost terminal end 48 of the combustion chamber interior be slightly offset towards the interior of the device, as related to the minimum internal diameter of the separate sleeve member 46. Stated another way, the diameter of the primary opening 32 should be slightly smaller than the minimum diameter of the upper end of the tubular duct means 12 so that a shock wave can travel past the openings 22 and 30 without disruption and without escape from the device. Although the sleeve member 46, with its diverging taper configuration, has been described as a separate member for insertion in the device, it can be appreciated that the uppermost end of the tubular duct means 12 can be formed to provide the desired taper for producing a venturi effect at the level of air in-

duction into the system. However, the arrangement which is shown in FIGURE 2 is especially useful because it permits careful adjustment of the inlet areas of the passageways 22 and 30. By inserting the separate sleeve member 46 to a desired level, portions of the individual passageways 22 and 30 can be cut off to provide more or less inlet area. Once the desired inlet areas are established, the separate sleeve member can be fixed in its position by a set screw 50, or by any other equivalent fastening device. Then, the tubular duct means 12 can be inserted so as to abut against a lower end of the separate sleeve member 46, and a series of set screws 52 can be used to fix the position of the tubular duct means relative to the combustion chamber portion of the propulsor device. The internal diameter of the tubular duct means is the same as the lowermost internal diameter of the separate member 46 so that a smooth internal passageway is provided in the tubular duct means.

In the embodiment illustrated in FIGURES 1 through 4, there is shown a typical arrangement for a propulsor device which utilizes hydrogen gas as a combustible fuel. The propulsor device of this invention permits a safe use of hydrogen gas as a primary fuel, and it can be appreciated that the combustion products of hydrogen gas do not contribute to air or water pollution, as is the case with many other fuels in present day use. However it has been found that a wide variety of fuels can be utilized in the propulsor device of this invention, and fuels in gaseous, liquid, and solid states will produce a shock wave in the device if admitted with a correct proportion of air or other gas for supporting combustion. When a gaseous fuel, such as pressurized hydrogen or butane, is being used in the device, the fuel supply may be in the form of a steel container which is sufficiently strong to contain a liquid form of the fuel at a very high pressure. The fuel supply container may include standard and known valving devices for releasing gaseous fuel from the container. Referring to the arrangement shown in FIGURE 1, the conduit 18 may be connected to valving devices associated with the pressurized container, and control means (which will be discussed with reference to FIGURE 13) will regulate the release of fuel from the container for induction into the propulsor device through separate conduits 20. As shown in FIGURE 4, four separate conduits 20 may be utilized to distribute hydrogen fuel from the central conduit 18 into the passageway 30 of the propulsor device. Of course, it is to be understood that if the fuel is delivered from a pressurized supply, it is actually forced into the propulsor device by the difference in pressure of the fuel as compared with the interior pressure of the propulsor unit. Other systems for admitting fuel into the propulsor device may rely upon an induction of fuel through the passageways 30 by the relatively low pressure conditions created in the device during and after each expulsion cycle. Although four secondary conduits 20 are illustrated in FIGURE 4 for admitting gaseous fuel into the system, any other desired number of conduits may be utilized to obtain a desired mixture of fuel and combustion-supporting gas in the device. The number of air inlet passageways 22 can be varied, and valving means can be provided for adjusting the total intake area of the passageways 22 and 30. Such valving means may consist of plate members which can be moved to partially, or totally, cover individual passageways, or certain passageways may be simply plugged to reduce the total area for admitting air or other combustion-supporting gas into the device. Also, as discussed above, the separate sleeve member 46 may be utilized to adjust the areas of all passageways 22 and 30.

FIGURES 5 through 7 illustrate a series of steps in a typical operation of the propulsor device of this invention. FIGURE 5 illustrates the propulsor device, as attached to a marine vessel, and it can be seen that a water column is supported within the tubular duct means 12 of the propulsor device. The uppermost level 56 of water

contained within the tubular duct means 12 may be higher or lower than the level of the body of water in which the device is operating, depending on the frequency of ignition of fuel mixture within the combustion chamber. However, it is important that the tubular duct means 12 have a sufficient length to provide an internal volume of space above the uppermost level 56 of the water which is greater than the volume of combustion and exhaust gases which will be expelled from the combustion chamber 10 by a detonation therein. This important relationship permits a free movement of a shock wave from the combustion chamber to the water level 56. The step illustrated in FIGURE 5 is representative of the beginning of a cycle of operation for the device, and subsequent steps will cause a rapid expulsion of the water column, or slug of water, from the tubular duct means 12 to propel the marine vessel to which the device is attached. FIGURE 6 illustrates the condition of the propulsor device of FIGURE 5 after a detonation has formed a shock wave within the device. The formed shock wave is delivered to the surface 56 of the column of water which was previously contained within the tubular duct means 12, and the impact of the shock wave with the column of water causes a very rapid expulsion, and the resulting increase in pressure at the outlet end of the tubular duct means 12, creates an efficient propulsive moment. After the water column and all combustion products have been expelled from the tubular duct means 12, relatively low pressure conditions are created within the combustion chamber 10. These low pressure conditions assist in an induction and admission of fuel and air into the combustion chamber for a subsequent ignition and detonation. It has been found that the initial impact of a shock wave with the surface 56 of the column of water contained within the tubular duct means produces secondary waves which are reflected back up the tubular duct means and into the combustion chamber 10. These reflected secondary waves contribute to the creation of a turbulence within the combustion chamber, and the created turbulence provides for a very efficient and complete mixing of fuel and air within the chamber. However, the turbulent conditions which are created are not sufficient to cause a residual, or premature, ignition of admitted fuel and air, and this is important to a successful formation of a shock wave during a subsequent ignition and detonation of the fuel-air mixture. FIGURE 7 schematically illustrates the admission, or induction, of fuel and air into the system during and after the initial expulsion of water from the tubular duct means. FIGURE 7 also illustrates the return of a new column of water into the tubular duct means as a result of the low pressure conditions which exist within the unit. The rate of return of water into the tubular duct means is substantially slower than the rate of expulsion of water from the propulsor device, and therefore, a net propulsive effect is obtained. The low pressure conditions which are created within the combustion chamber 10 after each detonation are sufficiently low to draw a new column of water all the way up to, and into, the combustion chamber itself, but this is normally prevented by timing controls which control the operation of the igniter means 24 so that a new ignition and detonation takes place before the new column of water has reached the combustion chamber 10. By adjusting the timing controls associated with the igniter means 24, the volume of water which is inducted into the tubular duct means 12 can be controlled, and this provides for a variable control of the propulsive effect of the propulsor device. The arrows which are shown in FIGURES 6 and 7 illustrate movement of fluids and movement of the propulsor device through a body of water. The propulsor device which is illustrated in FIGURES 5 through 7 also includes an augmenter means 60 which may be attached to the terminal outlet end of the tubular duct means to increase the efficiency of the pro-

pulsor device. However, the propulsive effect of the device of the present invention is so great that very substantial and efficient propulsion effects are obtained by a unit of the type illustrated in FIGURE 1 having no augmenter means attached. The augmenter means 60 is illustrated in greater detail in FIGURE 8.

Referring to FIGURE 8, the augmenter means 60 functions to increase the forward propulsion efficiency of the propulsor device during periods when water is being inducted into the tubular duct means 12 for a subsequent expulsion cycle. The augmenter means 60 has a frustoconical configuration, and is attached to the outlet end of the tubular duct means by strut members 62. Any desired number of the strut members 62 may be spaced about the outlet end of the tubular duct means for attaching the augmenter means 60 thereto. The strut members 62 may be airfoil shaped to reduce their resistance to movement through a body of water. The augmenter means is open-ended at both its leading and trailing ends, and the internal diameter x at the trailing end of the augmenter means 60 is approximately the same as the internal diameter of the tubular duct means 12, thereby avoiding any restriction of, or interference with, the expulsion of a slug of water from the open end of the tubular duct means 12. Arrows are indicated around the open end of the tubular duct means 12 to show a typical flow of water into the open leading end of the augmenter device 60, and then into the open end of the tubular duct means 12, for being inducted up into the tubular duct means 12. It has been found that the augmenter means of FIGURE 8 contributes to the forward propulsion efficiency of the propulsor device by drawing a substantial volume of a new quantity of water from a forward area of the tubular duct means rather than from a region which trails the open end of the tubular duct means. The general direction of movement of the propulsor device is indicated by a large arrow, and this forward movement, as created by each expulsion of water from the tubular duct means, causes a flow of water through the augmenter means 60. After each expulsion, there is a coasting period in which the tubular duct means is refilled, and a fresh quantity of water is drawn into the tubular duct means in accordance with the flow path indicated. Also, a Coanda effect is obtained from the relationship of the augmenter means 60 to the terminal end of the tubular duct means 12, and this means that water which is flowing past the open terminal end of the tubular duct means 12 has a tendency to turn inwardly towards the central axis of the open end of the tubular duct means. This effect assists in an induction of a fresh quantity of water into the tubular duct means after each expulsion cycle.

FIGURE 9 is a sectional view of an augmenter which may be connected to the end of a tubular duct to control the flow of liquid into and out of the duct. This arrangement may be used where the propulsor is used as a pumping device (for example, in irrigation uses) and a shroud 63 is provided to receive liquid into a first end 65 of the shroud for a subsequent discharge from an opposite end. A one-way valve means (symbolically represented at 67) of any known construction may be provided to close the outlet end of the shroud during periods that water is being re-induced into the tubular duct 12. A similar one-way valve may be provided at the inlet end of the shroud 63 in constructions where the tubular duct has no curved terminal end 14 but is merely connected to the shroud to form a T-shaped connection.

FIGURES 10 and 11 illustrate alternative constructions which may be incorporated in the propulsor device of this invention. FIGURE 10 illustrates a modified form of passageway 22 which may be milled, or otherwise formed, into the ring portion 34 of the unit. Of course, the passageways 22 may be of any other suitable configuration, and the use of the term passageway is not intended to be limited to a bore having a circular cross section. In addition, the ring portion 34 can be eliminated

from the construction, as shown in FIGURE 11, and the passageways 22 can be formed directly through wall portions of either the combustion chamber 10 or of the tubular duct means 12. However, it is important that air and fuel be admitted in relatively close proximity to the level of the primary opening 32 of the combustion chamber 10, and the FIGURE 11 arrangement shows such a relationship. FIGURE 11 also illustrates alternative fuel injection or induction means which are positioned to admit fuel through passageways 30 formed through wall portions of the combustion chamber 10. The passageways 30 may be of any configuration, and may consist of circular borings formed on axes which intersect the single high energy spark source of the igniter 24. By directing admitted fuel towards the igniter means 24, it is possible to protect the igniter means 24 from any moisture or water which may splash upwardly into the combustion chamber 10. Although the passageways 22, for admitting combustion-supporting gas into the device, have been illustrated as being open to an atmosphere surrounding the propulsor device, it is to be understood that combustion-supporting gas may be metered and admitted by way of conduits from any desired source. Thus, the entire device could be adapted for operation in a completely submerged attitude, and all fuel and combustion-supporting gas could be admitted into the system from sources which are isolated from the body of water into which the device is submerged.

FIGURE 12 illustrates a particular adaptation of the propulsor device of this invention to a hydrofoil construction 70. The hydrofoil construction may be of the type which is carried by a marine vessel for decreasing the draft of the vessel as the vessel is accelerated through a body of water. The combination which is shown in FIGURE 12 provides for both a propulsion and a lifting of a vessel by such a hydrofoil construction, and the hydrofoil may be connected to the vessel by struts 72. Alternatively, the tubular duct means portion 12 of the propulsor device may function as an interconnecting strut member between the hydrofoil 70 and the vessel to which it is attached. The tubular duct means 12 may have a streamlined outside configuration to improve its flow characteristics through a body of water. With the arrangement shown in FIGURE 12, slugs of water are periodically and rapidly expelled from the tubular duct means 12, as described above. In addition, the device has been modified to provide an inlet port 74 through a leading edge of the tubular duct means and at a level which is substantially in line with an upper surface 76 of the hydrofoil 70. The opening 74 functions to provide a means by which an upper boundary layer can be drawn off from the upper surface 76 of the hydrofoil 70 during each expulsion cycle of water from the tubular duct means 12. The rapid expulsion of water from the tubular duct means 12 will create a venturi effect at the opening 74 so as to entrain additional liquid from the upper surface 76 of the hydrofoil 70. This arrangement contributes to the lifting efficiency of the hydrofoil 70.

FIGURE 13 is a schematic representation of alternative uses to which the device of the present invention may be applied. For example, it is possible to admit molten metal, or other materials in a plastic state, into an induction distributor 80 as schematically illustrated in FIGURE 13. Such plastic state materials can be rapidly expelled from the tubular duct means 12 by detonations and shock wave formations to cause the plastic material to be driven from an open end of the tubular duct means. This arrangement may be used in metal forming applications wherein water may be expelled against a metal sheet to obtain desired configurations and shapes of a final product. Also, the propulsor may be used to expel water in riot control uses, and adjustments may be made in the operation of the device to assure a safe use which will not injure persons against which it is directed.

FIGURES 14 and 15 illustrate control devices which

may be associated with the propulsor device to achieve a safe and controlled operation of the device. For example, it is desirable to relate the admission of fuel and the operation of the ignition means 24 to one another so that one cannot overlap the other in its timed sequence of operation. This type of control may be effected by a switching means 90 which functions to actuate either circuit 92 or circuit 94 for an alternate sequence of operation. The switch means 90 may be operated by a trigger pulse generator which is variable in its timed sequence of operation, and thus the timing of igniter means 24 can be adjusted. The adjustment of the igniter means 24 automatically adjusts the alternate sequence of operation of circuit 94 to open solenoid valves 96 for admitting fuel into the combustion chamber 10. The switch means 90 and the coil 98 may be in the form of a transistorized ignition system, such as a Judson Electronic Magneto System. Preferably the solenoid valve 96 is of a type which can operate at relatively high frequencies with little maintenance, and a suitable solenoid comprises a guillotine type of mechanism which is periodically actuated (by cams, or otherwise) to engage and squeeze the conduit 20 sufficiently to shut off the flow of fuel therethrough.

FIGURE 15 graphically illustrates a sequence of operation for the propulsor device, and the timed operations of a coil 98 (of FIGURE 14) and of solenoid valves 96 are compared. It can be seen that each trigger impulse results in a charging of the coil 98 while the gas solenoid 96 is being operated to admit fuel into the system. At the end of each interval of admission of fuel into the system, the gas solenoid valves are shut off, and the coil 98 is discharged.

FIGURE 16 illustrates another system for controlling fuel supply and ignition to the propulsor device of this invention. The system of FIGURE 16 is connected to the propulsor device in the same manner as shown in FIGURE 14, i.e., conduit 20 admits fuel into the combustion chamber 10, and circuit 92 carries a timed impulse from a generator to a coil 98. The schematic illustration of FIGURE 16 shows a piston 102 which is reciprocated back and forth in a chamber for controlling and metering the flow of fuel from a pressurized fuel supply to the conduit 20. Fuel from a pressurized supply maintains a ball valve 104 in a normally closed position, but extreme movements of the piston (to the left as viewed in FIGURE 16) displaces the ball valve 104 out of its seated position so as to admit a quantity of fuel into the chamber in which the piston is operating. A projection is provided on the head of the piston to displace the ball valve 104. Movements of the piston in an opposite direction (to the right as viewed in FIGURE 16) cause the admitted quantity of fuel to be moved out of the piston chamber and through the conduit 20. Reciprocal movements of the piston are dictated by a rotating crank 106 connected to the piston by way of a connecting rod 108. The rotating crank 106 is mounted on a drive shaft 110. Impulses are relayed to the coil 98 by rotating movements of the drive shaft 110 relative to a generator. A surface portion of the drive shaft is coated, or otherwise constructed, to make and break a flow of current through the circuit 92. This may be accomplished in any well known manner, such as by providing insulated zones between non-insulated zones on the surface of the drive shaft so that current is delivered to contact brushes which are maintained in contact with the drive shaft while it is rotating. Current will be delivered in accordance with whether or not a non-insulated zone is exposed to a contact brush.

Although this invention has been described with reference to specific embodiments and examples, it is to be understood that equivalent structures may be substituted and obvious variations may be utilized. It is intended that such substitutions and variations be included within the scope of the general concepts and principles of this invention.

What is claimed is:

1. An improved propulsor device comprising:
a combustion chamber for receiving and detonating an ignitable fuel, said combustion chamber having a primary opening in communication therewith for admitting a fuel and gas mixture and for releasing combustion products and detonation forces from said combustion chamber,
a tubular duct means connected to the single opening of said combustion chamber for forming a communication between the combustion chamber and a body of liquid into which the tubular duct means extends, said tubular duct means having a terminal end which is open and which can be placed below the surface of said body of liquid for rapidly expelling slugs of liquid out of the tubular duct means after each detonation which takes place in said combustion chamber, said terminal end of said tubular duct means being curved relative to a main central axis of the tubular duct means so that the open end of the terminal end can be directed in a direction which is opposite to the direction of propulsion which is to be obtained from the propulsor device, at least one passageway formed through a portion of said device proximal to the connection between the combustion chamber and tubular duct means, said at least one passageway being above or isolated from said body of liquid in which said propulsor device is to be operated and having a function to admit a combustion-supporting gas into said tubular duct means and then into said combustion chamber after each detonation of ignitable fuel in the combustion chamber, and
fuel admission means communicating with said propulsor device for mixing an ignitable fuel with the combustion-supporting gas which is introduced into said combustion chamber.
2. The propulsor device of claim 1 wherein said tubular duct means has a substantially constant internal diameter throughout its entire length.
3. The propulsor device of claim 1 and including means for mounting the propulsor device on a marine vessel with a lower portion of said tubular duct means below the surface level of a body of water in which the marine vessel is to be operated, and with an upper portion of the tubular duct means and all of said combustion chamber isolated from the body of water in which the vessel and propulsor device are positioned for use so that water cannot normally enter the combustion chamber.
4. The propulsor device of claim 1 wherein said tubular duct means is of a sufficient length to support a column of water within its confines which extends above the level of said body of water in which the propulsor device is operating but which normally remains below the levels of said at least one passageway and said combustion chamber.
5. The propulsor device of claim 1 wherein said combustion chamber includes an igniter means for detonating a fuel mixture introduced into the combustion chamber.
6. The propulsor device of claim 1 wherein said igniter means is positioned at an end of said combustion chamber which is remote from and in substantial alignment with the center of said single opening connecting said combustion chamber to said tubular duct means.
7. The propulsor device of claim 6 wherein said at least one passageway through said tubular duct means is positioned in close proximity to said combustion chamber so that a combustion-supporting gas is drawn into said combustion chamber and thoroughly mixed with said ignitable fuel after each explosion in said combustion chamber.
8. The propulsor device of claim 1 wherein said com-

bustion chamber is generally tapered in its internal cross-sectional dimensions, said tapered combustion chamber converging in a direction extending from an initial ignition area within the combustion chamber towards said primary opening which communicates with said combustion chamber, so that a detonation shock wave is formed and strengthened within the combustion chamber prior to contact of the shock wave with liquid in said tubular duct means.

9. The propulsor device of claim 8 wherein the taper of the combustion chamber interior is approximately 15° as related to the central longitudinal axis of the propulsor device.

10. The propulsor device of claim 8 wherein the taper of the combustion chamber interior is within the range of 5° to 45° as related to the central longitudinal axis of the propulsor device.

11. The propulsor device of claim 8 wherein said tubular duct means has an internal gas space, above the average level of liquid inducted into said tubular duct, which is greater in volume than the internal volume of the combustion chamber.

12. The propulsor of claim 8 wherein said tubular duct has an internal diameter which is slightly greater than the diameter of said primary opening of said combustion chamber, at a level where said at least one passageway is formed through said tubular duct means.

13. The propulsor unit of claim 12 wherein said tubular duct has a slight diverging taper relative to said central longitudinal axis in a direction away from said primary opening and at a level downstream from said at least one passageway which is formed through said tubular duct.

14. The propulsor unit of claim 8 wherein a plurality of passageways for inducting combustion-supporting gas and for admitting fuel are formed through said tubular duct means at a level nearly adjacent to said primary opening of said combustion chamber.

15. The propulsor of claim 8 wherein fuel admission port means are provided through a wall of the combustion chamber.

16. The propulsor of claim 15 wherein said fuel admission port means are positioned to admit fuel on a line of travel which substantially intersects the position of an igniter means contained with the combustion chamber.

17. The propulsor device of claim 8 in combination with a hydrofoil structure, with the terminal end of said propulsor device being connected to a trailing edge of said hydrofoil, and including an induction inlet through a forward portion of the tubular duct means at a level approximately even with an upper surface of said hydrofoil structure.
